UNITED STATES PATENT OFFICE.

WILLIAM A. CAMPBELL, OF EAST SAGINAW, MICHIGAN, ASSIGNOR OF ONE-HALF TO A. F. BARTLETT & CO., OF SAME PLACE.

REVERSING-VALVE.

SPECIFICATION forming part of Letters Patent No. 324,222, dated August 11, 1885.

Application filed April 29, 1885. (No model.)

To all whom it may concern:

Be it known that I, WILLIAM A. CAMPBELL, of East Saginaw, in the county of Saginaw and State of Michigan, have invented new and useful Improvements in Reversing-Valve Attachments to Steam-Engines; and I do hereby declare that the following is a full, clear, and exact description thereof, reference being had to the accompanying drawings, which form a part of this specification.

This invention relates to new and useful improvements in twin-cylinder steam-engines; and the invention consists, mainly, in the construction and arrangement of the valves and valve-gear for correctly distributing the steam and controlling the movement of the valves by means of a lever in the hands of the operator, so as to adapt the engines for operating a saw-mill carriage, a hoist, an elevator, or for similar use requiring a constant and quick reversal of the engines and absolute control of their speed.

In the drawings which accompany this specification, Figure 1 is an elevation of the twin-engine, showing the side on which the valves and valve-gear are located, the valves of one engine being shown in section to show their construction and arrangement. Fig. 2 is a side elevation showing the main shaft with its connections. Fig. 3 is an enlarged view of the steam chest and valves. Fig. 4 is a detail specifically referred to hereinafter.

A A are the cylinders of two engines, symmetrically alike in all parts, and inclined so as to form a right angle with each other, and having their frames suitably connected and supported so as to form a single structure.

B is the main shaft, supported on top of the frame and common to both engines. C is a crank or crank-disk on the main shaft. D D are the connecting-rods of the engines, attached to the wrist of the crank, and E E are two valve-eccentrics, which actuate the valves of the engines, all these parts being of known construction and operation.

The valves and valve-gear are constructed and arranged as follows:

F is a hollow piston slide-valve operating in a cylinder steam-chest, G, from which the usual ports, a a, lead into the engine-cylinder.

This piston slide-valve has its seat formed like an ordinary D-valve, and it regulates the distribution of steam into the cylinder precisely in the manner of such a valve. Owing to its form, it is steam-balanced.

H is the exhaust-passage, which communicates with the exhaust side of the slide-valve, and I is the live-steam passages, through which the steam passes into the steam-chest G.

J is another steam-chest secured to the steam-chest G, and having the steam-supply pipe K leading into it. This steam-chest incloses a cylinder, L, in which the piston slide-valve M is seated. The cylinder L is open at both ends, and has the three ports N O P. The port N communicates through the exhaust-passage H with the exhaust side of the slide-valve F. The port O communicates through the passage I with the steam-space in the steam-chest G, and the port P leads into the exhaust-pipe Q.

The piston-valve M is a cylindrical D slide-valve. It operates in connection with the ports N O P in the following manner: In one of its two extreme positions (which is shown in the drawings) it connects the exhaust-port N with the exhaust-port O, and gives the live steam free access through the port P into the steam-chest G. In its opposite position the valve M connects the port P with the exhaust-port O, and opens the exhaust-port N to the live steam. Thus by reversing the valve M from the position shown in the drawings the exhaust side of the valve F becomes the steam side, and vice versa. The steam being thus reversed in the cylinder, the piston will also be reversed.

As the two valves M must be operated alike, they are connected together by a system of levers and connecting-rods, arranged as follows: The valve-rod of each valve is pivotally connected to a connecting-rod, R. Each of these connecting-rods is connected to one end of a bell-crank lever, S, the other ends of which are connected together by a connecting-rod, T. The respective arms of the bell-crank levers S are of equal length, and they form the same angles with their respective connecting-rods. This arrangement gives the valves M an equal throw.

U is a rock-arm secured to one of the bell-

crank levers S, and V is a connecting-rod pivotally secured to the rock-arm at one end, and to the hand-lever W at the other end.

By means of the hand-lever W the operator 5 controls the valves M simultaneously.

By the above-described arrangement the weight of the valves M and their valve-gear is balanced.

It will be observed that by moving the valve 10 M from one of its extreme positions toward the opposite one the steam is first gradually throttled until at mid-position, when it is entirely cut off from the cylinder; then steam is again admitted in a reverse direction and gradually increases until the valve is again fully 15 opened. Thus the speed and direction of the engine absolutely depend on the position and movement of the valve M. It will be further observed that the valve M, at whatever position 20 it may be placed, is always perfectly steam-balanced, so that it can be moved by hand without the slightest exertion. The perfect action of the valve M in these respects is a necessary condition for its practical use in 25 an engine for operating a saw-mill carriage or hoist, as the work of the engine is here entirely and constantly guided by the hand of an operator, whose work depends largely on the ease and promptness with which he can control 30 his engine.

As far as the construction and operation of the valves F and M are concerned, it is obvious that they are equally applicable to single engines, and I claim their application as such 35 as well.

For engines of large size I interpose between the hand-lever and the valve-gear a steam-piston for operating the reversing-valve by steam-power, as shown in Fig. 4, in which the 40 hand-lever operates a slide-valve, m, on the steam-cylinder n. When the steam is admitted on both sides of the piston, the engines are at rest, and if the valve m is thrown over to one side or to the other the engines are running 45 in one direction or the opposite. By means of this arrangement but little movement and

power are required by the operator to control his engines.

What I claim as my invention is—

1. The combination, with twin engines arranged at right angles to each other to form two sides of a triangle, with a single supply-pipe at the base, and a single main shaft at the apex, as shown, of a main slide-valve for each engine, and two reversing-valves interposed between the supply-pipe and the main valve, and arranged with their gear to counterbalance each other, as set forth. 50

2. In a twin-cylinder engine, the combination of the reversing slide-valves M M, connecting-rods R R T, and the bell-cranks S S, arranged in two connecting sets, each adapted to counterbalance the other, with a single actuating hand-lever, W, substantially as described. 60

3. In a twin-cylinder engine having valves F operated from a single shaft, the balanced reversing piston slide-valves M M, each arranged to counterbalance the other, and each having a cylindrical seat open at both ends, 70 and provided with ports N O P, combined with the steam-chests J, forming a steam-passage to both ends of the valve, and with a single operating mechanism for moving both valves simultaneously in the same direction, 75 as set forth.

4. The combination of the steam-balanced reversing slide-valves M, with their connecting-gear arranged to counterbalance the weight of valves and gear, all arranged substantially as 80 described.

5. In a twin-cylinder engine having a single main shaft and feed-pipe, the combination, with the valves E and connections with the main shaft, of the balanced reversing-valves M, 85 the rods R R T, bell-crank levers, and operating mechanism, as U V W, arranged to counterbalance, as set forth.

WILLIAM A. CAMPBELL.
